UNITED STATES PATENT OFFICE

WILLIAM B. NICHOLS, OF GRAHAM, TEXAS

UNDERREAMER

Application filed January 4, 1928. Serial No. 244,461.

This invention relates to improvements in under-reamers and more particularly to that type of under-reamers which is employed in drilling oil wells.

One of the objects of the present invention is to provide an under-reamer so constructed that it may be more readily inserted through the well pipe, preparatory to operation, than under-reamers of the ordinary construction, and in this connection the invention contemplates so mounting the cutters of the under-reamer that the same may be retracted and held in retracted position while the under-reamer is partly inserted into the well pipe, and the cutters then released to be automatically expanded to working position, upon downward movement of the under-reamer in the well pipe to a position to extend below the lower end of said pipe.

Another object of the invention is to provide an under-reamer so constructed that the cutters thereof may be readily removed and other cutters substituted therefor, so that cutters of different sizes may be employed and therefore the single tool may be adapted to cut bores of different diameters, in the oil bearing rock.

Another object of the invention is to provide an under-reamer so constructed that, on the up stroke of the tool, the cutters will be relieved of strain, at the beginning of said stroke, thus obviating any likelihood of the cutters being torn loose from the tool.

While the accompanying drawings and the description which is to follow, constitute a disclosure of the preferred embodiment of the invention, it will be understood that various changes may be made within the scope of what is claimed.

In the accompanying drawings:

Figure 1 is a view in side elevation of an under-reamer constructed in accordance with the present invention;

Figure 2 is a vertical longitudinal sectional view taken substantially on the line 2—2 of Figure 1 looking in the direction indicated by the arrows;

Figure 3 is a bottom plan view of the under-reamer;

Figure 4 is a horizontal sectional view taken

substantially on the line 4—4 of Figure 2 looking in the direction indicated by the arrows;

Figure 5 is a perspective view of one of the cutters of the under-reamer;

Figure 6 is a view similar to Figure 2 illustrating a means which may be employed in retracting the cutters at the time of introducing the under-reamer into the well pipe.

The under-reamer embodying the invention comprises a cylindrical body shell 1 which is exteriorly of a diameter nearly equal to the internal diameter of the well pipe through which the under-reamer is to be lowered to working position, and this shell is interiorly threaded near its upper end as indicated by the numeral 2 and houses a tubular barrel which is indicated by the numeral 3 and which is exteriorly threaded for a portion of its length as at 4 to adapt it to be threaded into the shell 1. The barrel 3 is provided with a bore indicated by the numeral 5 the lower portion of which is of increased diameter as indicated by the numeral 6, for a purpose to be presently explained, and the barrel is provided at its lower end, exteriorly, with a circumscribing flange 7 which abuts against the lower end of the shell body 1 and which, for a purpose to be presently explained, is provided, at intervals in its circumference, with notches indicated by the numeral 8.

The under-reamer further embodies a plunger including a stem 9 which is slidably fitted in the bore 5 of the barrel 3 and the lower portion of which is threaded as indicated by the numeral 10 and has adjustably fitted thereto a nut 11 provided in its under face with diametrically oppositely located notches 12 for the application of a spanner wrench whereby the nut may be adjusted upon the stem. A compression spring 13 is arranged upon the stem 9 within the enlarged portion 6 of the bore 5 of the barrel 3 and bears at its upper end against the shoulder which is provided at the upper end of the enlargement 6 of the bore and, at its lower end, bears against the nut 11, it being understood that the tension of the spring may be varied by adjusting the nut 11 and that the stem 9 may have upward sliding movement in the bore 5 of the barrel 3 against the tension of

the said spring, the spring however normally holding the plunger 9 yieldably in a downwardly shifted position and with the head of the plunger, which is indicated by the numeral 14, abutting against the upper end of the said barrel 3. The head 14 of the plunger is provided at its upper end with the usual conical threaded stud 15 for the connection of the drill rod of the drilling apparatus, so that reciprocatory motion may be imparted to the under-reamer after the same has been lowered through the well pipe and past the lower end of said pipe.

The cutters of the under-reamer are indicated in general by the numeral 16 and each comprises a body 17 having a shank 18 projecting from its upper side and formed with an opening 19 to accommodate a pivot pin 20 which is fitted therethrough and chordally through the barrel 3, near the lower end thereof, and transversely of one of a plurality of slots 21 which are provided in the said portion of the barrel to accommodate the said shanks 18 of the cutters. The body 17 of each cutter is preferably of segmental form and, when the cutters are in the projected positions shown in Figures 1, 2 and 3 of the drawings, the bodies project beyond the outer side of the shell 1 of the under-reamer, in position to act upon the rock to be drilled, and in order that the cutters may be reinforced when in this position, the upper side of each cutter, at opposite sides of the shank 18, is flat as indicated by the numeral 22 and abuts squarely against the lower end of the barrel 3 and the under side of the flange 7 at said end of the barrel, each of the cutters being formed at its upper end and immediately outwardly of the shank 18, with a lug or boss 23 which, in this position of the cutter, engages in the respective one of the notches 8. Each cutter 16 is provided, at the lower outer side of its body 17, with a cutting lip 24 having an arcuate, perpendicular outer face 25, and a flat under face 26, these faces defining, between them, a chipping edge 27. At this point it will be evident, and particularly by reference to Figure 6 of the drawings, that the pivot pins 20 for the cutters are freely inserted in openings provided for their reception, in the barrel 3 at the opposite sides of the slots in said barrel and that therefore the pins may be readily removed, when the barrel is removed from the shell 1. Therefore cutters of different sizes may be substituted one for another and the under-reamer adapted to undercut holes of various diameters, and in this manner the invention obviates the employment of a number of separate and distinct under-reamers for this purpose.

From the foregoing description of the invention it will be evident that, when the cutters are forced inwardly and an upward pull is exerted upon the plunger 9, the cutting

edges of the cutters may be brought to position within the circumference of the shell 1 and consequently readily inserted into the well pipe, and, when the under-reamer has been moved downwardly through the pipe 70 and the lower end of the under-reamer extends below the lower end of the pipe, the cutters will be automatically projected radially in an outward direction to active position.

Figure 6 of the drawings illustrates a convenient means whereby the cutters may be retracted and temporarily held in such position, prior to insertion of the under-reamer into the upper end of the well pipe, and in this figure the numeral 28 indicates hooks 80 which are equal in number to the number of cutters, as for example, three, and which are provided with overturned, inwardly projecting bills 29 at their upper ends and with eyes 30 at their lower ends, the eyes 85 providing means whereby cords 31 may be connected with the shanks of the hooks to exert a pull upon the hooks, when their bills are engaged in sockets 32 which may be formed in the upper ends of the bosses 23 of 90 the cutters. At this point it will be evident that by exerting a downward pull upon all of the cords 31, after the hooks have been engaged with the respective cutters, and holding the plunger 9 stationary, the same being 95 attached to the rod of the drill, the cutters may be caused to swing inwardly to the position shown in Figure 6, and at this time a cord 33 may be passed about the cutters and knotted so as to retain the cutters in this 100 position, temporarily, the hooks 28, at this time, being disengaged from the cutters. The lower end of the under-reamer may then be inserted into the upper end of the well pipe until the cutting edges 27, or the faces 25 105 of said edges are engaged in the upper end of the well pipe, whereupon the string or cord 33 may be severed and removed, and the under-reamer may then be bodily fed downwardly through the well pipe until it passes 110 the lower end of the pipe, whereupon the lower portion of the plunger 9, below the threaded portion 10, and which portion is tapered as illustrated in the drawings and indicated by the numeral 10', will wedge 115 between the inner edges of the shanks 18 of the cutters, which edges are, for this purpose, inclined, and cause outward swinging movement of the cutters about their pivots 20, to active position, the cutters being in 120 this manner restrained against inward displacement, on the down stroke of the under-reamer, but, on the up stroke, due to the momentary retraction of the plunger stem 9, being permitted to swing inwardly to clear 125 the surface of the rock.

Having thus described the invention, what I claim is:

1. An under-reamer comprising a barrel, a plunger including a stem slidably mounted 130

- in the barrel, the stem having a threaded portion, a nut threaded onto the said stem, a spring within the barrel bearing against the said nut and yieldably holding the stem in a downwardly shifted position, the stem being provided with a head engaging the upper end of the barrel and limiting the downward movement of the stem in the barrel, and cutters pivotally suspended from the lower portion of the barrel, the plunger stem having a tapered lower end portion for coaction with the inner sides of the cutters, upon downward movement of the plunger, to swing the cutters outwardly to active position. 5

2. An under-reamer comprising a barrel, a plunger including a stem slidably mounted in the barrel, cutters, pivotally suspended from the lower portion of the barrel, the cutters having shoulders engaging against the lower end of the barrel, in the outwardly swung position of the cutters, the said stem having a tapered lower end portion for coaction with the inner sides of the cutters, upon downward movement of the plunger, to swing 10 the cutters outwardly to active position, a spring coacting with the plunger and yieldably holding the same in a downwardly shifted position coacting with the cutters, the plunger stem having a threaded portion, 15 and an abutment adjustably threaded on said portion and engaged by one end of the spring and constituting means whereby the tension of the spring may be varied. 20

3. An under-reamer comprising a barrel, the said barrel being provided in its lower portion with vertically extending slots opening through its lower end, cutters having shanks pivotally suspended in the upper ends of said slots, the inner sides of the shanks 25 being inclined, a shell upon the barrel closing the outer sides of said slots, the outer sides of the cutter shanks being engageable against the said shell in the outwardly swung position of the cutters, the cutters having shoulders engageable beneath the lower end of the barrel in the outwardly swung position of the cutters, and a plunger including a stem slidably mounted in the barrel and having a tapered lower end portion for coaction with 30 the said inner sides of the cutter shanks to effect outward swinging of the cutters to active position upon downward movement of the plunger. 35

4. An under-reamer comprising a barrel, the said barrel being provided in its lower portion with vertically extending slots opening through its lower end, cutters having shanks pivotally suspended in the upper ends of said slots, the inner sides of the shanks 40 being inclined, a shell upon the barrel closing the outer sides of said slots, the outer sides of the cutter shanks being engageable against the said shell in the outwardly swung position of the cutters, the cutters having shoulders engageable beneath the lower end of the barrel in the outwardly swung position of the cutters, and a plunger including a stem slidably mounted in the barrel and having a tapered lower end portion for coaction with 45 the said inner sides of the cutter shanks to effect outward swinging of the cutters to active position upon downward movement of the plunger. 50

5. An under-reamer comprising a barrel, the said barrel being provided in its lower portion with vertically extending slots opening through its lower end, cutters having shanks pivotally suspended in the upper ends of said slots, the inner sides of the shanks 55 being inclined, a shell upon the barrel closing the outer sides of said slots, the outer sides of the cutter shanks being engageable against the said shell in the outwardly swung position of the cutters, the cutters having shoulders engageable beneath the lower end of the barrel in the outwardly swung position of the cutters, and a plunger including a stem slidably mounted in the barrel and having a tapered lower end portion for coaction with 60 the said inner sides of the cutter shanks to effect outward swinging of the cutters to active position. 65

In testimony whereof I affix my signature.
